UNITED STATES PATENT OFFICE.

AMOS FREDERICK DIXON, OF NEWARK, NEW JERSEY, ASSIGNEE, BY MESNE ASSIGNMENTS, TO WESTERN ELECTRIC COMPANY, INCORPORATED, A CORPORATION OF NEW YORK.

SELECTING APPARATUS AND SYSTEM.

1,215,918.

Specification of Letters Patent. Patented Feb. 13, 1917.

Application filed May 24, 1915. Serial No. 30,006.

To all whom it may concern:

Be it known that I, AMOS FREDERICK DIXON, a citizen of the United States, residing at Newark, in the county of Essex and State of New Jersey, have invented certain new and useful Improvements in Selecting Apparatus and Systems, of which the following is a full, clear, concise, and exact description.

10 This invention relates to selecting apparatus and systems, and its principal object is to provide an improved apparatus and system of the electromechanical type.

In accordance with its general features, 15 the invention contemplates current impulse collecting or distributing apparatus, wherein in an operating electromechanical structure successively brings a plurality of switches into operative position and then effects their 20 actuation, coöperating with a current controller and selecting mechanism.

The above and other objects of the invention will be fully set forth in the following description and claims, and will be 25 more readily understood by reference to the accompanying drawing in which is disclosed a specific embodiment particularly adapted for use in telegraph systems; the circuit arrangement being shown diagrammatically and parts of the mechanical elements being shown in perspective.

The mechanism, which may be used either as a current collector or distributor or both simultaneously, comprises a rotatable member 5 loosely mounted upon a suitable shaft 6. Member 5 is preferably in the form of a partial disk and carries near its circumference a plurality of switch members or contacts, each of which is adapted to be 40 engaged by a circuit completing member to form a plurality of current collecting or distributing switches. These contacts comprise a plurality of pins 11, 12, 13, 14 and 15, which, for convenience, will be called 45 collecting pins, and a plurality of companion pins 21, 22, 23, 24 and 25 which will be designated distributing pins. Collecting pins 11 to 15 inclusive are respectively associated with a current controller made 50 up of pole changers 31, 32, 33, 34 and 35, each pin being connected to the movable contact of its corresponding pole changer. The left-hand fixed contacts of all of the 55 pole changers are connected to the positive pole of a grounded and divided source of

energy 36, and the right-hand fixed contacts of these pole changers are connected to the negative pole of this source. Each of the distributing pins 21 to 25 inclusive is respectively connected to ground through the winding of an electromagnet 41, 42, 43, 44 and 45, which in their turn may control any desired form of selecting apparatus, as, for example, the character and operation selecting mechanism of a printing telegraph receiver.

The pole changers 31 to 35 inclusive of the current controller are selectively actuated to connect either positive or negative pole of source 36 to the corresponding collecting pins 11 to 15 inclusive by any suitable means, as, for example, the well-known selecting apparatus controlled by keys arranged in the form of an ordinary typewriter keyboard, or by any of the well-known automatic devices whose operation is controlled by a perforated paper tape or the like. Preferably the apparatus which controls the operation of the pole changers also effects the operation of a line switch 50 moving a contact 51 thereof from a fixed contact 52 to a fixed contact 53.

Secured to shaft 6 is a ratchet wheel 55 whose teeth are adapted to be engaged by a spring-tensioned operating pawl 56 secured to member 5 by a pivot post 57. The teeth of ratchet wheel 55 are likewise engaged by a stop spring 58 to prevent the backward rotation of shaft 6, as will be presently explained. A part of member 5, as previously mentioned, is removed, providing an abutting surface 59 which cooperates with a stop pin 60 to limit the movement of member 5, and an abutting surface 61 adapted to coöperate with a circuit controlling switch 62, for purposes to be hereinafter described.

Pins 11 to 15 inclusive go to form a plurality of current collecting switches, and pins 21 to 25 inclusive go to form a plurality of current distributing switches by coöperating respectively with one of a pair of circuit completing members in the form of contact springs 65 and 66. The conducting pins are successively brought in pairs into operative relation with springs 65 and 66, and are engaged and disengaged by these springs to mark the initiation and cessation of current impulses through the agency of an electromechanical device.

This device comprises an electromagnet 67, one terminal of whose winding is connected to a grounded source of energy 68 and which is provided with a spring-tensioned 5 pivoted armature 69. Armature 69 has an upward extension carrying contact springs 65 and 66 and another upward extension carrying a pair of escapement pallets 70 which are adapted to engage the teeth of 10 ratchet wheel 55.

The energy required to operate member 5 under the control of escapement pallets 70 is provided by a spring 75 secured at one end to any desired form of anchor, and at the 15 other end to member 5 through a pin 76. This spring tends to rotate member 5 and, through pawl 56, ratchet wheel 55 in the direction of the arrow, and when, after having been allowed to do so, as will be presently explained, it is again brought to full 20 tension, and the member 5 is returned to its normal position with surface 59 engaging stop 60 by a restoring electromagnet 77. This electromagnet is provided with a 25 spring-tensioned armature 78 pivoted at 81. Armature 78 is provided with an extension 79 which is adapted to engage pin 76 when armature 78 is attracted to return member 5, as mentioned above. During the return of 30 member 5 ratchet wheel 55 is prevented from following by stop spring 58, so that while member 5 has a reciprocating movement, ratchet wheel 55 moves always in the same direction. Armature 78 also controls 35 the operation of a switch 80.

There are also provided a pair of line relays 85 and 86, a restoration controlling relay 87, and a clearout relay 88. The windings of relays 85 and 86 provide parallel 40 paths from ground to contact 52 and through a suitable resistance 90 to contact 51 and transmission line L. Resistance 90 is so proportioned that it is approximately equal to the resistance of line L plus the resistance 45 of the windings of whatever electro-mechanical devices may be connected therein at a distant station. Relay 85 is provided with a pair of armatures 91 and 92, and relay 86 is provided with a single armature 50 93. Armatures 91 and 93 are grounded and coöperate with front contacts which are connected together, to one of the elements 55 of switch 62 and to one terminal of the winding of electromagnet 67 and one terminal of the winding of electromagnet 77. Armature 92 is connected to spring 66 and coöperates with a front contact which is connected to a grounded source of energy 94. Contact 53 of line switch 50 is connected 60 to spring 65.

One element of switch 62 may be grounded, as hereinafter described, and the other element is connected to a fixed contact 100 coöperating with a movable contact 101 controlled by and connected to one terminal of

the winding of relay 87, the other terminal of which is connected to a grounded source of energy 102. Relay 87 is provided with two armatures 103 and 104. Armature 103 coöperates with movable contact 101, and armature 104 coöperates with a front contact connected to one of the terminals of the winding of electromagnet 77. One terminal of the winding of relay 88 is connected to one of the elements of switch 80, the 75 other element of which is grounded, and the other terminal of this winding is connected to a grounded source of energy 105. Relay 88 is likewise provided with a pair of armatures 106 and 107. Armature 106 is grounded and coöperates with a back contact connected to armatures 103 and 104 of relay 87, while armature 107 is connected to one element of a clear-out switch 108, the other element of which is grounded and coöperates with a front contact connected to one 80 terminal of the winding of the relay 88.

The operation of the apparatus and system, when used as a combined current impulse transmitter and effect distributor, is 90 as follows: It will be assumed, for the purpose of this explanation, that relay 85 is polarized to operate only on positive current and relay 86 is polarized to operate only on negative current, and that a station at the 95 distant end of transmission line L is provided with polarized relays similar to 85 and 86 and distributing apparatus and selecting mechanism, such as hereinbefore described. Normally, all of the apparatus is 100 in the condition shown in the drawing with springs 65 and 66 engaging pins 11 and 21, respectively, and contact 51 of switch 50 in engagement with contact 52. When the key 105 or automatically controlled pole changers 31 to 35 inclusive are selectively actuated and line switch 50 is operated, so that contact 51 disengages contact 52 and engages contact 53, a circuit is completed from the positive or negative pole of source 36 110 through the movable contact of pole changer 31, pin 11, spring 65, contacts 53 and 51, and in parallel through transmission line L and the distant apparatus therein to ground, and resistance 90 and the windings 115 of relays 85 and 86 to ground.

Assuming that the movable contact of pole changer 31 has been moved from the right to the left-hand contact, the current flowing in the circuit just traced will operate only relay 85, which will pull up its armatures 91 and 92. Armature 91 completes a circuit from ground through the winding of electromagnet 67 to grounded source of energy 68, and armature 69 therefore is attracted. Armature 92 completes a circuit from grounded source 94 through spring 66, pin 21, and winding of electromagnet 41 to ground, causing this electromagnet to perform its proper function in 125 130

the selecting mechanism. The attraction of armature 69 causes one of the pallets 70 to be disengaged from a tooth of ratchet wheel 53, and the other pallet is thrown into a position to engage the next tooth. The movement of armature 69 also withdraws springs 65 and 66 from engagement with pins 11 and 21, and the previously traced circuits from sources 86 and 94 are interrupted, and the first impulse, which was initiated upon the engagement of contacts 51 and 53, is brought to an end.

The movement of pallets 70, momentarily releasing ratchet wheel 53, allows spring 73 to move member 5 one step in the direction of the arrow. The interruption of the circuit from source 86 through relay 85 has caused this relay to release its armatures 91 and 92. The retraction of armature 91 breaks the previously traced circuit through the winding of electromagnet 67, and armature 69 is retracted by its spring. The return of armature 92 breaks the circuit from source 94 to spring 66. The return of armature 69 causes pallets 70 to allow spring 73 to move member 5 a further step in the direction of the arrow, and springs 65 and 66 are brought into engagement with pins 12 and 22.

If pole changer 31 had remained in normal condition upon the engagement of contacts 51 and 53, negatively polarized relay 86, instead of relay 85, would have been operated, and member 5 would have been caused to take two steps precisely as hereinbefore described. Electromagnet 41, however, would not have been energized, and the selecting mechanism, as far as this element is concerned, would remain inactive.

Springs 65 and 66 are now in engagement with pins 12 and 22, and the second impulse of current to line L and relays 85 and 86 is initiated. The character of this impulse is determined by the condition of pole changer 32. If the impulse is positive, relay 85 is again operated, resulting in the energization of electromagnet 42, and member 5 is caused to take two more steps as before. If the current is negative, however, relay 86 alone is energized, resulting in the movement of member 5 but not in the energization of electromagnet 42.

These operations continue, the character of the impulses being determined by the remaining pole changers 33, 34 and 35, and electromagnets 43, 44 and 45 being energized if the corresponding pole changer provides positive current from source 86, but not being energized if negative current is supplied. In moving around in the direction of the arrow, member 5 has caused pin 76 to approach extension 79 of armature 78, and surface 61 has approached spring 62. Upon that deenergization of electromagnet 67, which results in switches 65 and 66 engaging

pins 15 and 25, to initiate the last impulse, surface 61 operates switch 62, and a circuit is prepared from grounded source 102 through the winding, movable contact 101 and back contact 100 of relay 87, through switch 62 to the coöperating front contacts of armatures 91 and 93. This circuit is completed to ground when either relay 85 or 86 is energized by current from source 86, which causes relay 87 to pull up its armatures 103 and 104. Armature 104 completes a circuit from grounded source 68 through the windings of electromagnets 67 and 77, front contact and armature 104 of relay 87, and back contact and armature 106 of relay 88 to ground. This circuit prolongs the energization of electromagnet 67 which has been previously caused to remove springs 65 and 66 from pins 15 and 25 to terminate the last impulse by the usual circuit through armatures 91 or 93. The flow of current causes the energization of electromagnet 77 which attracts its armature 78, whose extension 79 engaging pin 76 rotates member 5 in a direction opposite to that of the arrow until surface 59 engages stop 60. During this backward movement, ratchet wheel 53 is held from backward rotation by stop spring 58 and pawl 56 rides over the teeth of the ratchet wheel. The attraction of armature 103 completes a holding circuit for relay 87 through its movable contact 101 and the back contact and armature 106 of relay 88, and the continued energization of relay 87 is made independent of the line relays or of switch 62, which, of course, is opened as soon as the return of member 5 begins.

When armature 78 is depressed sufficiently to cause the engagement of surface 59 and stop 60, it closes switch 80 completing a circuit from grounded source 105 through winding of relay 88, which pulls up its armatures 106 and 107. The attraction of armature 106 opens the previously traced holding circuit for relay 87 and operating circuits for electromagnets 77 and 67. The consequent deenergization of electromagnet 67 causes springs 65 and 66 to reengage pins 11 and 21, while the deenergization of electromagnet 77 allows the spring of armature 78 to remove extension 79 from engagement with pin 76, and this part of the apparatus is in a condition to begin a new operation. Armature 107 of relay 88 completes a holding circuit for the relay from grounded source 105 through clear-out switch 108, which circuit may be broken by the subsequent operation of switch 109, whereupon all of the apparatus is again in normal condition, ready to begin a new selective action.

When the selecting apparatus is acting solely as a distributor of effects controlled by current impulses over transmission line L, the operation is precisely as heretofore

described, except that polarized relays 85 and 86 are selectively actuated by current from line L instead of from source 36, and the condition of line switch 50 is unaltered.

5 The invention claimed is:

1. A selecting system comprising an electromechanical current-distributing mechanism, a transmission line providing a succession of current impulses, a plurality of 10 distributing switch members carried by said mechanism, a pair of circuit closers associated therewith, and an electromagnet for simultaneously actuating said circuit closers and causing a step-by-step movement of said switch members to distribute current determined by the current impulses from over the line.

2. A selecting system comprising current control means, an electromechanical 20 current-distributing mechanism associated therewith, a plurality of collecting switch members carried by said mechanism, a pair of circuit closers associated with said members, and means for actuating said circuit closers and causing a step-by-step movement of said mechanism whereby said members are brought into engagement with said

circuit closers sequentially to form a succession of current impulses.

3. A selecting apparatus comprising electromechanical selecting mechanism, a plurality of circuit contacts associated therewith, means coöperating with said contacts to complete energizing circuits for said mechanism, and an electromechanical device, for simultaneously actuating said means and causing a step-by-step movement of said contacts to distribute the effects of a succession of current impulses. 30 35

4. A selecting apparatus comprising a plurality of contacts carried by a rotatable member, an escapement wheel associated with said member, a circuit completing member adapted to coöperate with said contacts, an escapement lever coöperating with said wheel, and an electromagnet for simultaneously actuating said circuit completing member and said escapement lever for causing said circuit completing member to successively act upon said contacts. 40 45 50

In witness whereof, I hereunto subscribe my name this 21st day of May A. D., 1915.

AMOS FREDERICK DIXON.
